R. RAY.
Excavator.

No 13528.

Patented Sept 4, 1865.

UNITED STATES PATENT OFFICE.

RICHARD RAY, OF LOUISPORT, KENTUCKY.

MODE OF OPERATING AND DUMPING EARTH-CARS.

Specification of Letters Patent No. 13,528, dated September 4, 1855.

To all whom it may concern:

Be it known that I, RICHARD RAY, of 5
Louisport, in the county of Hancock and
State of Kentucky, have invented certain
new and useful Improvements in the Mode
of Constructing Embankments Not Hitherto
Known; and I hereby declare that the
following is a full, clear, and exact description
of the same, reference being had to the
10 accompanying drawings, forming a part of
this specification, of which—

Figure 1 is a plan, and Fig. 2, an elevation
and side view.

The nature of my improvement consists
15 in the arrangement of a pair of removable
rail ways, or tracks, the manner of working
the cars for transporting the earth
thereon, and the self opening and closing
thereof—so that by the draft of a horse
20 moving in one direction attached to a rope,
passing over suitable pulleys and drums, an
alternate car filled with earth can be drawn
and unloaded on the end of one track, while
an empty car on adjacent track is returned
25 to the opposite end thereof, thus allowing
one of the cars to be unloaded, while the
other is traveling and receiving its load.

My invention consists in making use of
a shifting rope, F, provided with ball or
30 block thereon, I whereby the cars are
moved.

I will proceed to explain the construction
and mode of operating as follows: The
horse having been attached to the swing
35 tree A, and the rope B, passes around a pulley
C, on the anchor D. He is started and
draws the rope from the windlass E, which
in turning winds the rope B', in a contrary
direction upon the windlass. This move-
40 ment causes the rope F, to wind on the
drum G; said rope passing around pulleys
H H, at the opposite end of the track, and
brings the blocks I, attached to the rope F,
in contact with the upright bars or rack, K
45 situated in one end of the car, No. 1, the
block I, catching behind any two bars of K,
hold sufficiently firm to draw the empty car
back to the place of filling, (viz to the right
hand side of the figure) when the rack end
50 of the car passes under the pulley L, this
pully raises the block I and rope above the
ends of the bars of the rack, and the car is
arrested; the block and rope continuing to

move, passes around the pulleys H, H, until
the block is brought in contact with the end 55
of the loaded car No. 2, of the adjacent
track, in passing the racks they are so con-
structed as to allow the ball to pass them
and bring the block immediately in contact
with the end of the car. The horse still con- 60
tinuing to draw in the same direction, the
rope is entirely unwound from one side or
end of E and transferred or wound upon the
shaft in another direction. By this means
the loaded car No. 2 has been brought to the 65
left while No. 1, remained at the right hand
side receiving its load. The horse by this
time is near the end of the rail way; and
now on turning him around and his direc- 70
tion reversed, unwinds the rope B' from
the windlass and reverses those on the drums.

It will be noticed that in traveling one
half of the space between this anchor and
the end of the track, he returns the empty 75
car or No. 1, and in passing over the remain-
ing space toward the anchor he draws the
loaded car or No. 2, of the other track to the
place of deposit. Thus performing in each
trip the movement of an empty and a full 80
car upon their respective rails, the neces-
sary changes having been effected by the
moving ball I or block attached to rope F.

The cars are filled by hand or otherwise
but the delivery of their contents is effected
by automatic means. 85

O, is a port rising between the inner rail,
of the two tracks, so situated that it clears
the wheels of the cars, but shall trip the
lever closing the bottom of the cars when
said lever strikes the post. 90

The liberation of the swing bottom of the
cars is effected as follows: Fig. 3, exhibits
the reverse or underside of the car of which
d d are the side rails; e e, cross framing; a
95 a, two boards filling the width of the bot-
tom; b b b b, hinges allowing the bottom to
open downward.

f f, f f, are bolts secured on flaps a a.

g, g, are hasps on cross pieces e e having
slight motion so as to allow the hasp to be 100
moved outward in releasing the end of f f.

h h are suitable slap springs whose office
is to retain the hasp in position over the end
of bolts f, f.

n, is a lever pivoted at 2 and m also a 105
lever pivoted at 3. The length of m is suffi-

cient to project beyond the side of the car and allow it to come in contact with a post O between the tracks.

r, is a rod connecting m and n.

5 The opening of the bottom a a is by the end of lever m, striking the post O which throws those levers against the hasps g, g, and releases the bolts f, f, and thus leaves the bottom unsupported at liberty to fall 10 by their hinges.

By reference to Fig. 1, will be seen springs 4, 4, affixed to the inside of the rails of the track whose object is to break the violence of the fall of a a; 5, 5 shows angular guides 15 against which the ends of the bottoms a a strike as the empty car is moved on its return, those guides effecting the return of a a to their place by the ends of the bolts passing the spring hasp g, g, and the car is 20 ready to return to the place of receipt of earth.

Having thus fully described my improvements what I claim as my invention and desire to secure by Letters Patent is—

1. The method of operating alternate 25 trucks, upon a double rail way track by the several devices, as hereinbefore described.

2. I also claim the automatic delivery of the loaded cars constructed as described by the several devices thereon as set forth in 30 combination with a post O situated between the tracks.

3. I further claim the device for closing the bottoms a a of the cars as described.

In testimony whereof I have hereunto 35 signed my name before two subscribing witnesses.

RICHARD RAY.

Witnesses:

JOHN F. CLARK,
SAM'L. GRUBB.
